UNITED STATES PATENT OFFICE.

ALFIO RAPISARDI, OF BOSTON, MASSACHUSETTS.

BRUSH.

Application filed February 6, 1924. Serial No. 690,978.

To all whom it may concern:

Be it known that I, ALFIO RAPISARDI, a citizen of the United States, residing at Boston, in the county of Suffolk and State of Massachusetts, have invented certain new and useful Improvements in Brushes, of which the following is a specification.

This invention relates to brushes, and is especially concerned with fountain brushes 10 of the type used in painting.

It is the chief object of the invention to devise a brush of this type which can be cleaned more thoroughly and conveniently than brushes of this character as heretofore 15 constructed, which can be manufactured economically, and which can be conveniently repaired.

The nature of the invention will be readily understood from the following description 20 when read in connection with the accompanying drawing, and the novel features will be particularly pointed out in the appended claims.

The single figure of the accompanying 25 drawing is a vertical, cross-sectional view of a brush embodying the invention in the form at present preferred, some parts of the brush being shown in elevation.

The construction shown comprises a hollow head 2 having a handle 3 extending from one end thereof, the handle also being hollow and grooved at its upper end to receive the hose or tube which supplies paint, varnish, or other liquid to the brush. Assuming that this brush is of the round type, the lower end of the head will be tubular in form. Fitting within this head is a valve block 4 having a peripheral flange 5 projecting from its lower end and overlying the end 30 of the head 2. The brush body is separate from, and independent of, this block, and includes a body of bristles 6 confined between an inner metal tube 7 and an outer metal sleeve 8. In the process of assembling 35 these parts, the portions of the bristles between the tube and the sleeve are embedded in glue, or some suitable adhesive, and a tube or sleeve 9 of wood, fibre, or metal is driven into the position shown in the drawings to wedge the bristles firmly against the sleeve 8. When the adhesive has hardened or set, the bristles will be secured firmly in place. Projecting from the upper end of the sleeve 50 8 is a flange 10 which abuts against the flange 5 of the valve block, as clearly shown in the drawing. Both the valve block and

the brush body are removably secured to the head 2 by a collar 12 which is threaded on the head and is constructed to clamp the flanges 5 and 10 firmly against the lower end 60 of the head.

For the purpose of conducting the paint, or other liquid being used, from the hollow head into the body of the bristles, the valve block 4 has a nipple 14 extending from the lower end thereof to which a flexible rubber tube 15 is connected, both the nipple and the part 4 having a passage therethrough for the flow of paint into the tube. The flow of paint is regulated by a valve 16 arranged 70 to fit in a seat formed in the upper end of a block 4 and guided partly by a stem 17 that projects into the paint passage and partly by an extension 18 which projects through a hole formed in a brace 19. This brace extends entirely across the space in the head 2 and is either soldered or riveted to the head. An adjusting screw 20 is threaded through 75 the wall of the head 2 and bears on the upper end of the part 18 of the valve, while a spring 21 located below the valve serves to lift it off its seat and to hold it normally in contact with the inner end of the adjusting screw. Consequently, by turning the screw 20 the flow of paint to the brush may 80 be adjusted very accurately.

It will now be evident that in order to clean the brush it is merely necessary to unscrew the collar 12, then remove the brush body and the valve block and wash all these parts in turpentine or any suitable cleaning liquid. Since all the parts are exposed and readily accessible, it is an easy matter to clean them very thoroughly. The parts of the brush may then be reassembled, this operation requiring but an instant, and the device is then ready for use again. If desired, the brush body may be replaced by another of the same construction. The fact that the brush body and the valve block 90 are independent of each other, is of advantage not only in cleaning the brush, but also in renewing the bristle body or brush body when it becomes worn. The other parts of the device are preferably made of metal of a suitable character and thus will 95 last almost indefinitely.

While I have herein described the best embodiment of my invention that I have so far devised, I do not wish to be limited to the exact details of the construction shown. For instance, in making an oval or 100

flat brush of this type, it is merely necessary to make the proper changes in the shape of the parts and to secure the collar 12 to the head 2 by screws arranged to enable the collar to clamp the flanges 5 and 16 to the head, as above described.

Having thus described my invention, what I desire to claim as new is:

1. In a fountain brush, the combination of 10 a hollow head, a handle extending from one end of said head, a valve block supported in said head, a brush body independent of said block but having one end thereof abutting against said block, said body and block having flanges overlying the outer end of said head, and a collar arranged to clamp the flanges of said body and block against the end of said head, said block having a passage therethrough for conducting liquid from 15 said head into said brush body.
2. In a fountain brush, the combination of 20 a hollow head, a handle extending from one end of said head, a valve block supported in

said head, a brush body independent of said block but having one end thereof abutting 25 against said block, said body and block having flanges overlying the outer end of said head, a collar threaded on said head and serving to clamp the flanges of said body and block against the end of said head, a 30 nipple projecting from said block into said brush body, said nipple and block having a passage therethrough, a valve controlling the flow of liquid through said passage, and an adjusting screw carried by said head 35 and arranged to adjust said valve.

3. A brush body comprising a body of bristles, an inner tube around which said bristles are disposed at one end of the body, an outer sleeve encircling the body of 40 bristles at said end of the body, said bristles being secured firmly between said tube and sleeve, and an attaching flange projecting laterally from the periphery of said sleeve.

ALFIO RAPISARDI.
